UNITED STATES PATENT OFFICE.

HENRY W. DEDELS, OF WINNIPEG, MANITOBA, CANADA.

SHOE-POLISHING DEVICE.

No. 873,515.

Specification of Letters Patent.

Patented Dec. 10, 1907.

Application filed April 6, 1907. Serial No. 366,805.

To all whom it may concern:

Be it known that I, HENRY W. DEDELS, subject of the King of Great Britain, residing at Winnipeg, in the Province of Manitoba and 5 Dominion of Canada, have invented new and useful Improvements in Shoe-Polishing Devices, of which the following is a specification.

This invention relates to a shoe polishing 10 device of that character which includes a receptacle in the body thereof for holding liquid polish that is supplied as needed to a sponge or dauber connected with the receptacle.

15 The invention has for one of its objects to improve and simplify the construction of devices of this character so as to be comparatively simple and easy to manufacture, easy to manipulate and so designed that liquid 20 polish can be applied to the shoes without soiling the fingers or clothing or dropping the liquid on the floor.

A further object of the invention is the 25 employment of a polishing brush that is detachably connected with the chambered body or receptacle of the device so that it can be taken off as desired for use and secured in position when not in use and thus form a unitary article.

30 Another object of the invention is to provide a simple means for supplying liquid to the sponge and also means for preventing the sponge from becoming dry and soiled.

With these objects in view and others, as 35 will appear as the description proceeds, the invention comprises the various novel features of construction and arrangement of parts as will be more fully described herein-after and set forth with particularity in the 40 claims appended hereto.

In the accompanying drawing, which illustrates one of the embodiments of the invention, Figure 1 is a vertical section partly in elevation of the polishing device. Fig. 2 is 45 a vertical transverse section thereof. Fig. 3 is a detail sectional view of the means for attaching the dauber to the neck of the device.

Similar reference characters are employed 50 to designate similar parts throughout the several figures of the drawing.

Referring to the drawing, 1 designates a chambered body of any suitable material that is provided at its top near one end with a hollow boss 2 that is exteriorly threaded to receive a tubular neck or valve casing 3 having its lower end counterbored and

tapped to engage the external threads on the boss 2. This neck or casing 3 has a vertically extending bore 4 through which the liquid polish feeds to the sponge or dauber 5 secured in any suitable manner to the neck 3, as for instance by a sheet metal collar 3' that grips the sponge or dauber as shown in Fig. 3, there being suitable fastenings 3" for attaching the collar to the neck 3. Seated on the 60 boss 2 is a rubber gasket 6 for preventing leakage of the fluid. The neck 3 has a transverse tapering chamber 7 in which is fitted a conical plug cock 8 adapted to register by means of the port 9 therein with the feed passage 4, when it is desired to moisten the dauber. After the dauber is sufficiently moistened, the cock 8 is turned so as to positively cut off the supply of liquid polish.

To prevent the dauber 5 from becoming 75 dry or coated with dust when not in use, a screw cap 10 has a threaded engagement with the neck 3 for completely enveloping the dauber. Obviously, when the dauber is to be used, the cap 10 is first removed and 80 then by holding the body 1 in one hand, the dauber can be rubbed over the surface to be coated with the polish.

To polish the coated surface, a dry brush 85 designated generally by 11, is employed. The body 12 of the brush is provided with a plate 13 of sheet metal suitably secured to the back of the body and extending at its longitudinal edges beyond the latter. These extending portions of the plate are bent outwardly in 90 the form of hooks or semi-cylindrical flanges 14 that are adapted to engage corner beads 15 projecting laterally from the top of the body 1. By this means, the polishing brush 11 is connected or disconnected with the body 95 1 by a relative sliding movement. The curved portions 15 of the plate 13 serve as means whereby the polishing brush can be firmly gripped by the hand when used for polishing. When the polishing brush is not 100 in use, it is in the position shown, but when it is to be used, it is removed from the body 1 by sliding it outwardly in a direction away from the dauber.

I have described the principle of operation 105 of the invention, together with the device which I now consider to be the best embodiment thereof, but I desire to have it understood that the device shown is merely illustrative and that such changes may be 110 made when desired as are within the scope of the claims.

Having thus described the invention, what I claim is:—

- 5 1. A polishing device comprising a liquid containing receptacle provided with an opening and an externally threaded boss at the said opening, a neck provided with a passage communicating with the opening, one end of the neck having a threaded engagement with the boss, a plug-valve controlling the passage of the neck and arranged with its axis at right angles to the passage and removable with the neck for permitting the receptacle to be re-filled through the opening, and a dauber secured directly to 10 the neck and removable therewith.
2. The combination of a liquid containing vessel having a filling and discharge opening, a neck removably connected with the body and communicating with the opening, a valve carried by and removable with the neck, a screw thread on the extremity of the neck, a dauber rigidly secured to the neck, and a cap for the dauber secured to the neck by the said screw thread.

In testimony whereof, I affix my signature in presence of two witnesses.

HENRY W. DEDELS.
